UNITED STATES PATENT OFFICE

147,730

DESIGN FOR A COMBINED CANDLE AND TRAY

Mary C. Hussey, Mount Vernon, N. Y.

Application August 9, 1945, Serial No. 121,344

Term of patent 3½ years

(Cl. D73—1)

To all whom it may concern:

Be it known that I, Mary C. Hussey, a citizen of the United States, residing in Mount Vernon, county of Westchester, and State of New York, have invented a new, original, and ornamental Design for a Combined Candle and Tray, of which the following is a specification, reference being had to the accompanying drawing, forming part thereof.

In the drawing, Figure 1 is a perspective view of a combined candle and tray showing my design; Figure 2 is a vertical section thereof, taken at the position indicated by lines 2—2 in Figure 1.

The dominant features of my design reside in the portion shown in full lines.

I claim:

The ornamental design for a combined candle and tray, substantially as shown and described.

MARY C. HUSSEY.
